UNITED STATES PATENT OFFICE

JOHN J. MADDEN, OF CHARLESTOWN, MASSACHUSETTS

DESIGN FOR A FORK

Application filed November 17, 1930. Serial No. 37,692. Term of patent 7 years.

To all whom it may concern:

Be it known that I, JOHN J. MADDEN, a citizen of the United States, residing in Charlestown, in the county of Suffolk and State of Massachusetts, have invented a new, original, and ornamental Design for Fork, of which the following is a specification, reference being had to the accompanying drawing, forming part thereof.

The figure is a plan view of a fork, showing my new design.

I claim:

The ornamental design for a fork, as shown.

JOHN J. MADDEN.
